Marshall B. Lloyd
BY Arthur Nichols
ATTORNEY

UNITED STATES PATENT OFFICE.

MARSHALL B. LLOYD, OF MENOMINEE, MICHIGAN.

DESIGN FOR A TABLE OR SIMILAR ARTICLE.

56,182.

Specification for Design.

Patented Aug. 24, 1920.

Application filed April 2, 1920. Serial No. 370,885. Term of patent 14 years.

To all whom it may concern:

Be it known that I, MARSHALL B. LLOYD, a citizen of the United States, resident of Menominee, county of Menominee, and State of Michigan, have invented a new, original, and ornamental Design for a Table or Similar Article, of which the following is a specification, reference being had to the accompanying drawing, forming a part thereof, and wherein the figure is a perspective view of my new design.

I claim:

An ornamental design for a table or similar article substantially as shown.

MARSHALL B. LLOYD.
